UNITED STATES PATENT OFFICE.

SWITS CONDÉ, OF OSWEGO, NEW YORK.

DESIGN FOR A KNIT FABRIC.

SPECIFICATION forming part of Design No. 14,001, dated June 26, 1883.

Application filed April 25, 1883. Term of patent 7 years.

To all whom it may concern:

Be it known that I, SWITS CONDÉ, of Oswego, in the county of Oswego, in the State of New York, have invented new and useful Improvements in Design for Knit Fabric, of which the following, taken in connection with the accompanying drawing, is a full, clear, and exact description.

This design consists in a novel arrangement of square blocks knitted in fabric in parallel rows and isolated from each other by intervening stripes, the blocks of each row being disposed intermediately of those of the two adjacent rows, as represented in the accompanying drawing, which illustrates a piece of fabric knitted in accordance with my design.

A denotes the square blocks, which may be of any desired size, said blocks being arranged in parallel rows and isolated from each other by intervening stripes, as shown, and the blocks of each row being disposed intermediately of those of the two adjacent rows, as above set forth.

I do not claim the arrangement of blocks disposed in parallel rows in juxtaposition to each other, as I am aware the same is not new; but

What I do claim is—

The design for knitted fabric, consisting of square blocks arranged in parallel rows, separated by intervening stripes, the blocks of each row being disposed intermediately of those of the adjacent rows, substantially as shown and described.

In testimony whereof I have hereunto signed my name and affixed my seal, in the presence of two attesting witnesses, at Oswego, in the county of Oswego, in the State of New York, this 3d day of April, 1883.

SWITS CONDÉ. [L. s.]
